Inventor:

Ludwig F. von Sazenhofen

Patented Nov. 15, 1927.

UNITED STATES PATENT OFFICE.

LUDWIG FREIHERR VON SAZENHOFEN, OF NUREMBERG, GERMANY, ASSIGNOR TO THE
 FIRM KARL ROHRSEITZ, METALLWARENFABRIK, OF ZIRNDORF BI NUREMBERG,
 BAVARIA, GERMANY,
 TOY TALKING MACHINE.

Application filed November 22, 1926, Serial No. 150,118, and in Germany August 13, 1926.

The present invention relates to a mechanism for driving toy talking machines, it being a special feature of said mechanism that it comprises only a few and simple parts and can therefore be manufactured easily and at low cost. All mechanisms of this kind hitherto known have the disadvantage that they are of very intricate nature and therefore expensive to construct, due to the use of complicated gears and regulating means. The cost of such a mechanism of the old type which complies even with the most moderate demands exceeds by far the cost of a complete talking machine according to the present invention.

The present invention allows to construct a mechanism for toy talking machines, which consists of only few and simple parts, so that this driving mechanism can be easily manufactured at a low price. It is an essential feature of the present invention that the driving of the toy talking machine is effected by a crank handle with special means interposed for securing a satisfactory degree of uniformity in the revolutions of the revolving table supporting the record, the irregularities due to hand drive being completely compensated.

The annexed drawing shows by way of example a toy talking machine according to the present invention, in which Figs. 1 and 2 illustrate the driving gear in a cross section and in a longitudinal section respectively.

The toy talking machine consists of the casing *a* and the sound receiving tube reproducing the sound waves. In the casing *a* a vertical shaft *c* is journaled carrying at its upper end a horizontal rotating table *b* adapted to take up a record. On this shaft *c* a friction disk *d* is loosely mounted co-acting with a further friction disk *i*, which is fixed on a horizontal shaft *e*, the projecting end of which is shaped to form a crank

handle *f*. This friction disk *d* is maintained automatically in frictional gear with the further friction disk *i* by means of a spiral spring *g* provided on the lower part of the vertical shaft *c*. Above the loosely mounted friction disk *d* a further spiral spring *h* is arranged on the vertical shaft *c*, said spring being attached with its one end to the loosely mounted friction disk *d* and with its other end to the vertical shaft *c* below the rotating table *b* which is heavy enough to serve as flywheel. Owing to this resilient intermediate connecting spring member *h* between the friction disk *d* and the driven vertical shaft *c* with the heavy flywheel the irregularities of the hand drive are completely compensated and a good degree of uniformity is secured.

What I claim is:

A driving mechanism for toy talking machines comprising in combination a casing receiving the driving mechanism; a vertical shaft journaled in said casing and adapted to support on its upper end a rotating table; a friction disk mounted loosely on the said vertical shaft; a horizontal shaft journaled in the casing and shaped to form with its projecting end a crank handle; a further friction disk fixed on said horizontal shaft and adapted to engage with the friction disk on the said vertical shaft; a spiral spring arranged above the loosely mounted friction disk on the said vertical shaft and adapted to engage with its one end with the loosely mounted friction disk and with the other end with the vertical shaft; a further spiral spring provided below the friction disk on the vertical shaft and adapted to maintain the friction disk automatically in frictional gear with the disk on the said horizontal shaft.

In testimony whereof I affix my signature.
 LUDWIG FRHRR. von SAZENHOFEN.
